ENCLOSURE FOR VENDING MACHINES OR THE LIKE

Harvey J. Smith, Greensboro, N.C., assignor to Modern
Metal Products Company, Greensboro, N.C., a corpo-
ration of North Carolina

Filed Oct. 17, 1958, Ser. No. 53,017

Term of patent 14 years

(Cl. D52—3)

FIG. 2

FIG. 3

Figure 1 is a front perspective view of an enclosure for vending machines or the like embodying my new design;

Figure 2 is an end perspective view taken from the righthand side of Figure 1; and

Figure 3 is a rear elevational view of the enclosure for vending machines or the like of Figures 1 and 2.

The dominant features of my new design reside in the solid line portions of the drawing.

What I claim is:

The ornamental design for an enclosure for vending machines or the like, as shown and described.
